UNITED STATES PATENT OFFICE

ANDREW GOOD, OF LOS ANGELES, CALIFORNIA

SLUG-CASTING TYPESETTING-MACHINE OPERATION

Application filed July 14, 1928. Serial No. 292,622.

This invention relates to improvements in linotype machines and more particularly to means for operating the keys thereof and has for its object to provide a simple, efficient and inexpensive device of this character.

Another object of this invention is to provide improved mechanism in a linotype machine for replacing the conventional linotype key-board by means of a standard typewriter keyboard.

Another object of this invention is to provide means in a linotype machine for adapting the present linotype keys to a standard typewriter arrangement of keys.

15 A further object of this invention is to provide a keyboard as an auxiliary or supplementary attachment to the present style of linotype key-board for the purpose of dispensing with special skill in the operation of the linotype machine.

A further object of this invention is to provide means for removably mounting the auxiliary key-board upon the key-board of a conventional linotype machine.

25 A still further object of this invention is to provide mechanism magnetically controlled for manually operating the keys of a standard linotype machine thru the medium of auxiliary keys.

30 Another object of this invention is to provide shift keys on the auxiliary key-board with an arrangement for translating the action of the shift keys into operation of the proper keys on the linotype machine.

35 Another object of this invention is to provide mechanical key pushers for operating the keys of the linotype machine, said key pushers being magnetically and electrically controlled.

40 With the above and other objects in view my invention consists in the combination, arrangement and details of construction disclosed in the drawings and specifications, and 45 then more particularly pointed out in the appended claims.

In the drawings wherein similar reference characters designate similar parts throughout the respective views,

50 Figure 1 is a plan view of the key-board,

Figure 2 is a top plan view of a magnet hanger,

Figure 3 is a side elevation of my invention,

55 Figure 4 is a sectional fragmental detail view showing the shift key arrangement,

Figure 5 is a side elevation of the spacer keys,

Figure 6 is a side view of a spring arm,

Figure 7 is a side view of a supporting arm,

Figure 8 is a side elevation of a key pusher, 60 and

Figure 9 is a diagrammatic view of the circuit arrangement.

Referring to the drawings which are merely illustrative of my invention a base board 65 or key board is designated 10 having an inclination when applied upon the keyboard of a linotype machine. One of the hangers 11' for this key-board is shown in Figure 3, being designated 11' and the angular lug 13 thereof is secured by rivets 12 to the base board 10 by reason of which the vertically disposed hanger 11' holds the baseboard in inclined position, the lower rightangular portion 14 of this hanger being operatively secured to part of the linotype frame.

A prop 16, is attached in operative manner to the other end of the base board 10 and is vertically disposed; two such props may be employed on either side of the baseboard, the lower ends of which are respectively formed with the recesses 17 in which is disposed the assembling elevator lift rod of the linotype machine so that this rod 15 serves to support the lower front part of the baseboard 10. 75

In this manner the frame or baseboard 10 is caused to be supported in surmounted position directly over the key board of the linotype machine, the keys of the latter being designated 34. With the baseboard 10 disposed and mounted in this manner it will be seen that same can be removed at any time. It will be understood that linotype machines will be built so as to eliminate the present keyboards found on them in favor of the improved key board forming the subject-matter of this invention.

A plurality of keys 18 are provided for depressible action upon the key board or base board 10, and these keys follow the exact 100

order and disposition of the usual keys of the standard types of typewriters so that typists accustomed to handling and operating typewriters or the like may instinctively operate linotype machines by depressing the keys 18 instead of the usual typewriter keys, the concordance between the linotype and standard typewriters being brought about by my invention. The keys 18 are securely mounted upon the extreme outer ends of leaf spring arms 19 which are secured at their inner ends by fasteners 22 to the blocks 23 which are or may be insulator blocks. The shape and arrangement of the spring arms 19 is such that they normally support the keys in a horizontal plane.

Besides the keys 18 devoted to the usual letters and numbers and punctuation marks shown in Figure 1 there are the usual typewriter shift key lever having the key 20 and the latching key 21 therefor. A series of electro-magnets 25 are provided, one for each particular key of the series of keys on the key-board; each magnet 25 is strung securely upon the under side of the board 10 by a fastener of suitable construction 24 secured into this board and serving to position securely the rightangular portion 26 of a hanger 27 made of strap iron or the like whose lower portion 28 serves as a fulcrum bearing for a key-pusher or depressor 29. Each depressor consists of the armature end 31 arranged normally in spaced but contiguous relation with respect to the magnet 25, and the downwardly curved spring metal finger 32 terminating in the curved key-engaging toe 33. This depressor 29 is lever shaped being pivoted centrally upon the hanger portion 28. The toe 33 of each depressor 39 may, if desired, rest upon the adjacent key 34 of the linotype machine which it is designed to operate. The magnets are thus secured insulated so as to hang from the base board 10 so that when the baseboard is removed the magnets and other parts of my invention are removed as one unit.

The shift key arrangement is described as follows. The shift key 20 is secured upon a bell crank lever whose vertically disposed arm 52 carries the key proper, and whose remaining arm 47 is designed to make electrical contact in its arcuate sweep with any of a number of contacts, say the three contacts 49 mounted upon the arcuate shaped strap 48 operatively secured upon the under side of the board 10. Pivoted upon the arm 47 of the bell crank lever and shift key device is a push rod or bar 38 carrying the latching key 21, and formed intermediate its ends with an integral hook 40a, 43 designating the pivotal point of attachment of push bar 38 upon the arm 47 of the bell crank lever. A spring 45 connects the rod or bar 38 and the arm 47 for joint movement, a pivot 51 fulcruming the arm 47 upon a fixed hanger 50 also secured

to the under side of the board 10. The base board 10 is formed with a slot 42 for the push bar 38 to move in another slot 53 being formed there in for the lever 52 to move in, while a narrow slot 40 is formed upon this board 10 serving to receive detent-fashion, the hook 40a of the bar 38.

The spacer depressible key is designated 54, and alongside the same is the em spacer, 55, and alongside the latter is the en spacer 75 key 56. These keys are all in alinement. These three keys determine the operation of the proper em or en spaces or of the space band of the linotype machine. At each end of each of these spacer members is a screw pin 57 tapped into this member and also secured in the lower base board; alongside of this screw pin is another pin screwed into the member 54 as at 59, while an alining pin 60 is secured into the base board 10. A spring 85 58 is coiled around pin 57 which holds the spacer member spaced from the base board requiring depression of this spacer member before the spring is tensioned, which spring of course restores the spacer member to normal position when pressure is removed from the spacer member.

The electrical circuit includes a magnet for each key in the series of keys; a switch for closing the circuit to the magnet and a pusher 95 or equivalent device for releasing the matrices. Referring to Figure 9 it will be seen that a battery or source of electricity 62 is employed, and from one side of this battery runs a wire 64 from which connect wires 65, 100 67 to the contacts 36 of the key board frame 10, the circuit however being open between wires 65, 67 due to the key 18 being normally spaced out of engagement with the fixed contact 36. Wire 67 runs to the magnet 25, 105 from which runs the wire 66 to the wire 63 which runs back to the other side of the battery. In the same way the shift keys control magnets which operate the key pushers or the matrix operating selective parts of the 110 linotype machine.

In operation the operator familiar with the use and operation of any standard typewriter, depresses the keys 18, or shift keys 21, 20 for the large caps or 20a, 21a for the small caps, and in this manner will cause the matrices of the linotype machine to be operated selectively and interchangeably as called for by the characters of the text. In depressing any particular key 18 this key flexes the spring arm 19 sufficiently to make the key 18 and the particular contact or switch 18 interengage; thereupon the circuit is closed thru the battery or generator 62 to the particular magnet associated with this 125 key; thereupon this magnet becomes energized and draws to itself the armature end 31 of the particular pusher 29, and in drawing this end of the lever in the curved toe 33 is depressed, thereby depressing the ap- 130

propriate linotype key 34 and operating the proper matrix to cast the proper character printed on the key depressed in the first place; in this connection it will be noted that 5 the magnet may control the operation of any device designed to operate the proper matrices whether keys 34 be used or not. When the spacer members 54, 55, and 56 are operated the particular size of space required is provided for in the line cast on the slug; and when operating the particular shift key say shiftkey 20, in depressing lever 52 against the tension of spring 11b secured to board 10 at one end and to lever 15 52 at the other end, this lever in turn draws downwardly the latching lever 38 so its hook 40a will snap automatically, against the tension of the spring 45, into slot 40 of the board 10, thereby locking the lever 52 in set position until lever 38 is depressed again to release shift key 20. Thus the caps, lower case or small caps are cast. I do not limit myself to the exact details of construction disclosed herein but claim all variations falling within 20 the purview of the claims in a slug casting machine.

In this application, and disclosure it should be borne in mind that in any linotype machine, intertype and linograph in use today 30 the keys thereon are multiplied at great length and bear no relationship in order and arrangement to the keys of the standard typewriter. In any such slug casting typesetting machine many years of practice are required 35 before a linotype operator attains a proficient rate of speed, whereas typists on standard typewriters attain very great speeds at the expenditure of a fraction of the time and nervous energy occasioned by the linotype operator. My invention brings about great 40 simplification and facilitation in the setting of small capitals on the typesetting machine by providing a shift key to permit the operation of small capitals from the same key-board as the one used for lower case and capital letters. This works an innovation in the 45 operation of linotype machines. Thus any typist accustomed to speedily operating the standard typewriter may operate the linotype machine without previous study or practice and with very little diminution of speed. It is intended to construct the novel key-board in a slug casting linotype machine to 50 replace the key-board now found on such machines and this may be done even by dispensing with keys at all so long as it is possible to selectively and manually control the operation and intervals of activity of the 55 particular matrices which will form the characters desired on the slugs cast. Instead of having to reach far out as on present makes of typesetting machines to depress desired keys the novel key-board becomes the real 60 key-board of an existing typesetting machine 65

and reduces to small compass the size of the key-board.

What I desire to claim and secure by Letters Patent is:—

1. An auxiliary linotype key-board comprising a plurality of spring supported keys, a plurality of magnets associated in staggered relation with said keys, of the main linotype keyboard, an electrical circuit in which said magnets are included, switches controlled by said spring-supported keys, and pivotal pushers controlled by said magnets selectively, for depressing the linotype keys. 70

2. A device as described consisting of a key board removably attachable over the keys of a linotype machine, a series of spring arms secured upon said key-board, keys carried yieldably and terminally by said spring arms, an electrical circuit, magnets severally connected to said electrical circuit, contacts for closing said circuit engaged by the several keys selectively, said magnets being selectively energized by the engagement of key and contact, and means normally resting upon the keys of the linotype machine and separately controlled by said magnets for operating the linotype keys. 80

3. Mechanism for operating linotype machines in standard typewriter fashion consisting of an auxiliary key-board surmounting the linotype keys, means attaching said key-board upon a linotype over the keys of the latter, linotype key depressors normally resting upon the linotype keys, magnets interposed between said depressors and the keys of the auxiliary keyboard for energizing said magnets to selectively control the latter, and circuit closing devices for energizing said magnets controlled by said auxiliary board keys selectively. 95

4. An auxiliary key-board for linotype machines consisting of a base, a plurality of depressible keys and shift keys arranged in standard typewriter order, springs opposing the depression of said keys, selectively, a group of magnets, one associated with each key, means controlled by said keys selectively for energizing said magnets and lever-shaped pushers associated with said magnets having armatures attracted by said magnets and linotype key engaging parts to depress the latter. 100

5. In a device as described the combination of a frame, an arcuate shaped plate, contact pins arranged on said plate having electrical connections to a circuit, a bell crank lever having one arm pivoted so as to actually sweep across said contact pins selectively, magnets controlled by the several contact pins when contacted, a key board having keys for depressing said lever, a depending arm on said frame on which said lever is pivoted, a shaft lever pivoted on the mentioned lever arm-depressible from above said keyboard and having an intermediate hook, a spring con- 110 115 120 125 130

necting both levers, a key board on the shift lever and a slotted plate fixedly mounted in the slot in which said hook is constrained to engage.

- 5 6. In combination with a base board a series of magnets dependingly carried thereby, a series of individual detents pivoted fix-
edly so as to be attracted movably by said magnets selectively key pushers pivotally
10 carried by said detents designed to rest upon linotype keys, a standard typewriter set of keys arranged in surmounted relation depre-
singly upon said base board, and electrical means actuated by said last set of keys selec-
15 tively for energizing said magnets selectively.

In witness whereof he has hereunder set his hand this 26 day of May, 1928.

ANDREW GOOD.
